ELECTRICAL TESTING SYSTEM.

1,237,476.

Specification of Letters Patent. Patented Aug. 21, 1917.

Application filed December 21, 1916. Serial No. 138,169.

To all whom it may concern:

Be it known that we, HENRY P. CLAUSEN and CHARLES L. GOODRUM, citizens of the United States, residing at Mount Vernon, in the county of Westchester and State of New York, and at New York, in the county of New York and State of New York, respectively, have invented certain new and useful Improvements in Electrical Testing Systems, of which the following is a full, clear, concise, and exact description.

This invention relates to electrical testing systems, and particularly to that class of systems which is used in telephone exchanges for routine tests on telephone apparatus.

The object of the invention is the provision of means for making periodic tests on the connector switches of an automatic telephone exchange to detect and cause to be remedied, or to record all cases of unstandard conditions of a certain nature which are encountered.

After a connection has been established between two subscribers, and the calling subscriber has abandoned the call, but the called subscriber has failed to replace his receiver on its hook, the connector switch concerned in the connection, as well as the called line, are said to be in an unstandard condition. It is necessary to relieve, or remedy, this condition as soon as possible. Periodic manually conducted tests for detecting such held connectors are unsatisfactory, and result in a detriment to the service.

Automatic routine tests may be performed with the apparatus and means disclosed herein, with the result that, in most cases, the unstandard condition will be detected and remedied before a complaint can be lodged.

In the drawings, the part above the broken line diagrammatically represents the circuits of a well-known connector switch, and that part below the broken line diagrammatically represents an arrangement of the testing and recording means.

In the preferred form of the invention there is provided a testing means which is responsive to a changed electrical condition at one point only in the circuit of the connector switch. If, during a routine test, an unstandard condition is encountered, the re-

sponse of the testing means places a howler tone on the talking conductors of the held connector switch, which is intended to summon the responsible party. If this party, in response to such a summons, replaces his receiver on its hook, no record of the unstandard condition is made. If, on the other hand, the unstandard condition is not remedied within a predetermined length of time such condition is recorded, and the testing device is advanced into association with the next connector switch.

There are three conditions in which such an automatic connector switch as is shown in that part of the drawing above, the broken line may be found during an automatic routine test. It may be found: first, in an idle condition, second, in a busy condition, and third, in a condition created by the abandonment of the call by the calling party, where the called party has failed to replace his receiver on its hook.

In the idle condition, the switch will be substantially as shown in the drawing, that is, all side-switch arms will be in first position, and all magnets and relays deenergized and the off-normal switch open.

With such a switch in a busy condition, the line relay LR^1 , under control of the calling line, will be energized; the slow relay 10, controlled by the line relay LR^1 , will be energized; relay 5, whose function it is to extend the talking conductors through to the called party, will be energized, and the relay LR^2 , controlled by the called party, will be energized.

These conditions may best be understood by the following short description of the operation of such switch in extending a connection from the calling line to a called line.

Let it be assumed that the switch shown has been seized by a selector switch in the well-known manner. A path of low resistance is thereby completed between conductors 1 and 2, which results in the establishment of a circuit from ground, battery, the left-hand winding of relay LR^1 , the normal contact and inner lower armature of line relay LR^1 , conductor 1, the path of low resistance mentioned, conductor 2, the innermost upper armature and normal contact of relay LR^2 , the right-hand winding of line relay 105 LR^1 , and thence to ground. Relay LR^1 at

tracts its armature and establishes a circuit from ground, armature and alternate contact of relay LR^1 , the winding of slow release relay 10, to battery and thence to ground. 5 Slow release relay 10 is energized in this circuit and completes a connection from ground, contact and outermost armature of relay 10, test wire TW, and thence over well-known circuits, to the winding of a relay in 10 the line switch concerned in this connection (not shown), to battery, and thence to ground.

The calling party now dials to transmit a series of impulses, these impulses being short 15 openings of the path of low resistance spoken of. Line relay LR^1 , in response to such impulses, causes its armature to rapidly vibrate between its alternate and normal contacts, whereby a circuit is intermittently established 20 between ground, the armature and normal contact of relay LR^1 , inner armature and alternate contact of relay 10, winding of relay 11, the winding of primary magnet PM, the side-switch arm 4 in its first position, 25 the upper armature and contact of relay 13, to battery and ground. Magnets 11 and PM are energized in this circuit. Magnet 11, however, is slow to release, and does not respond to the separate impulses 30 transmitted through its winding and, therefore, remains energized until after such impulses have ceased. On the other hand, magnet PM, being fast, responds to each separate impulse, and steps the brushes of the 35 connector switch to the terminals of the desired group in the well-known manner.

The energization of the slow release relay 11 results in the establishment of a circuit from ground, armature and contact of relay 40 11, the winding of relay 6, to battery and thence to ground. Relay 6 controls the movement of the side-switch arms, and, upon its energization, moves the side-switch arms into their second position. This occurs after 45 the sending of this first series of impulses in response to the retraction of the armature of relay 11.

The subscriber now dials a second time and the consequent vibration of the armature of line relay LR^1 between its normal and its alternate contacts results in the transmission of impulses through the circuit described, except in this case such impulses travel through the winding of the 55 secondary magnet SM instead of the primary magnet PM, from thence through the side-switch arm 4 in the second position, to battery and ground, over the circuit previously traced. Under control of the secondary magnet SM, the brushes 8 and 9 are driven into contact with the terminals of the desired line.

The energization of relay 11 during the sending of this second series of impulses 60 energizes the relay 6 in the manner hereto-

fore described, and upon its deenergization at the end of the series of impulses, the side-switch arms 3 and 4 are moved into third position. A circuit is thereupon established from ground, the side-switch arm 3, the armature and contact of relay 6, winding of relay 5 to battery and ground. Relay 5 attracts its armatures and thereby extends the talking conductors of the connector switch to the brushes 8 and 9, and thence to the 75 conductors of the called subscriber's line.

At the same time a circuit is established from ground, interrupter I^1 , winding of relay 7, the side-switch arm 4 in its third position, the upper armature and contact of relay 13, to battery and ground. Relay 7, under the influence of the interrupter I^1 is 80 intermittently energized and deenergized. During the interval of energization, a circuit is completed from ground, the upper 85 alternate contact and armature of relay 7, upper armature and contact of relay 5, the brush 9, through the conductors and signaling apparatus of the called subscriber's substation, to the brush 8, contact and lower armature of relay 5, lower armature and alternate contact of relay 7 to a source of ringing 90 current. Through this circuit the bell of the called subscriber's substation is operated.

When, in response to the summons of his telephone bell, the called subscriber removes his receiver from its hook, and when the interrupter I^1 is in such a position that the relay 7 is deenergized, a circuit is established 95 from ground, battery, the upper winding of relay LR^2 , the upper normal contact and armature of relay 7, upper armature and contact of relay 5, brush 9, through the lines and apparatus of the called subscriber's substation, to the brush 8, contact and lower armature of relay 5, lower armature and normal contact of relay 7, lower winding of relay LR^2 , to ground. The relay LR^2 is energized 100 in this circuit and reverses the polarity 105 of the current traveling over the conductors 1 and 2 of the calling subscriber's substation in a manner and for a purpose well-known 110 in the art. At the same time relay LR^2 completes a circuit from ground, contact and outer armature of relay 10 test wire TW, outermost upper armature of relay LR^2 , the winding of relay 13, to battery, and thence 115 to ground. Relay 13 is energized in this circuit and attracts its armatures and opens 120 at its upper armature and contact the circuit for relay 7. The energization of relay 13 also results in the establishment of a locking circuit for itself from ground at the contact and outermost armature of relay 10, 125 contact and lower armature of relay 13, winding of relay 13, to battery and thence to ground.

The relay 7 is not, therefore, again energized and the talking conductors of the con- 130

5 nector switch are maintained in steady connection with the brushes 8 and 9, whereby a conversation between the calling and the called subscriber may take place.

10 Suppose now that both subscribers hang up their receivers. The connection set up and established through the connector switch, shown herein, will be ended and the switches concerned will return to normal in the well-known manner. In this case, the 15 line relays LR^2 and LR^1 , under the control of the two subscribers, as heretofore described, will be deenergized. The ground on the test wire TW, at the contact and outermost armature of relay 10, under control of relay LR^1 , will be removed, thereby allowing the line switch and other selector switches to release. At the same time a ground will be placed on the release magnet 15 through a circuit extending from ground, the armature and normal contact of relay LR^1 , innermost armature and normal contact of relay 10, the off-normal contact 12, the lowermost armature and contact of relay LR^2 , the winding of magnet 15, to battery and thence to ground, whereupon this connector switch will be released.

20 If, on the other hand, the called subscriber fails to replace his receiver on its hook, then only relay LR^1 will retract its armature and the ground placed on the circuit just described will have to travel through the winding of relay 14 in series with the winding of magnet 15, since the direct circuit extending between off-normal switch 12 and the relay 15 is open at the outermost lower armature and contact of relay LR^2 . Relay 14, however, is of such high resistance that the current traveling therethrough is insufficient to cause the energization of magnet 15, but is sufficient to cause the energization of relay 14. Relay 14 thereupon attracts its armature and establishes a circuit from ground, the armature and contact of relay 14, winding of relay 13, to battery and thence to ground. This ground also extends through the lower armature and contact of relay 13 to the test wire TW, thus holding the line switch and selector switches concerned in this connection.

25 The third condition in which this connector switch may be found is, therefore, apparent from the foregoing description. The ground exists on the circuit between the off-normal contact 12 and the winding of relay 14. Relay 14 and line relay LR^2 are still energized under the control of a called subscriber.

30 Referring now especially to the part of the drawing below the broken line, it will be seen that from each connector switch three conductors are led to a set of terminals t' , t^2 and t^3 ; the terminals t^2 and t^3 leading to the conductors which extend through the 35 armatures and contacts of relay 5 to the

brushes 8 and 9; the terminal t' leading to the point in the circuit of the connector switch which, from the previous description, will be recognized as being connected to the ground only when the condition for which 40 the test is being carried on occurs.

45 There is a set of brushes b' , b^2 and b^3 which are arranged to travel over and make contact with the terminals t' , t^2 and t^3 . These brushes are driven from one set of 50 terminals to another by a stepping magnet 16, and extend the circuits from the connector switch to the testing apparatus through the contacts and armatures of relay 17.

55 The operation of this testing apparatus may be described as follows:

60 A hand switch H is provided for putting such apparatus into operation. The left-hand member of this switch provides a circuit from ground through the interrupter I^2 to the winding of the motor magnet of the sequence switch 18, to battery and ground. Through this circuit the sequence switch is 65 stepped forward one step at a time.

65 Suppose that the brushes b' , b^2 and b^3 first come in contact with a set of terminals t' , t^2 and t^3 connected to an idle connector switch. Since no ground appears on the terminal t' , neither relay 19 nor 20 will be energized in any position of the sequence switch during this test. As position 1 is reached a circuit will be established from ground, battery, right-hand member of switch H, sequence switch contact 30, winding of relay 100 70 17, normal contact and armature of relay 21, to ground. Relay 17 will be energized in this circuit in position 1 only, and will attract its armatures 22, 23 and 24. When position 2 is reached a circuit will be established from ground, battery, the right-hand member of hand switch H, sequence switch contact 31, winding of relay 21, the normal contact and outermost armature of relay 19 75 to ground. Relay 21 is energized in this 105 circuit and will remain energized in all positions of the sequence switch 18 from 2 to 12, thus deenergizing the relay 17 in these positions.

80 As position 12 is passed and position 13 110 entered a circuit will be established from the ground, winding of stepping magnet 16, sequence switch contact 32, the right-hand member of hand switch H to battery and thence to ground. Stepping magnet 16 advances the brushes b' , b^2 and b^3 into contact with the set of terminals connected with the next switch to be tested.

85 Let us assume that in this case the connector switch is involved in a through connection from a calling subscriber to a called subscriber. No ground in this case will be connected to the terminal t' since the relay 10 is energized. Therefore, the sequence switch 120 90 18 will pass all of its positions as just de- 136

scribed; and the stepping magnet 16 will advance the brushes b' , b^2 and b^3 to the next set of terminals to be tested.

We will now assume that the connector switch is held by a called subscriber on a connection which has been abandoned by the calling subscriber. A ground will be placed on terminal t' from the armature and normal contact of relay LR^1 , inner armature and normal contact of relay 10, off-normal switch 12 to t' .

In position 1 of the sequence switch 18 relay 17 will be energized as heretofore described. A circuit will also be established between the ground at terminal t' through the brush b' , the contact and armature 24 of the relay 17, sequence switch contact 33, winding of relay 19, the right-hand member of hand switch H, to battery and ground. The relay 19 will attract its armatures and hold them in this position either until the sequence switch has passed position 12, or the called subscriber has replaced his receiver on its hook. As position 2 is reached the circuit for relay 21, heretofore described, will now be found open at the outermost armature and contact of relay 19; hence relay 17 will maintain its armatures attracted throughout positions 1 to 12, inclusive, as indicated at sequence switch contact 30. As position 6 is reached a circuit is established leading from the middle armature and contact of relay 19, condenser C, sequence switch contact 35, armature 22 and associated contact of relay 17, brush b^3 , terminal t^3 , normal contact and upper armature of relay 7, the upper armature and contact of relay 5, brush 9, through the circuit provided by the called subscriber's substitution apparatus, brush 8, contact and lower armature of relay 5, lower armature and normal contact of relay 7, terminal t^2 , brush b^2 , contact and armature 23 of the relay 17, sequence switch contact 34, contact and innermost armature of relay 19, secondary winding of transformer T, and thence to the middle armature of relay 19. The primary winding of transformer T provides a source of alternating current of such high frequency that a current induced in the secondary and flowing through the circuit just described will so actuate the receiver of the called subscriber's telephone set that a "howl" will be produced therein. This is designed to attract the called subscriber's attention, who may thereupon replace the receiver on its hook.

Should this happen the connector switch will be restored to its idle condition, whereupon relay 19 will be deenergized and in turn the relay 21 will be energized. The attraction of its armature by relay 21 removes, through the deenergization of relay 17, the testing apparatus from connection with the connector switch and when the sequence

switch 18 finally arrives at the thirteenth position, the brushes b' , b^2 and b^3 are advanced to a new set of terminals.

If, on the other hand, the subscriber should not replace the receiver upon its hook before position 12 of the sequence switch 18 is reached, then a circuit will be provided from ground at terminal t' through the brush b' , contact and armature 24 of the relay 17, sequence switch contact 36, the winding of relay 20, the right-hand member of hand switch H, to battery and ground. Relay 20 will be energized in this circuit and will thereupon establish a circuit leading from ground, armature and contact of relay 20, winding of relay 21, sequence switch contact 31, right-hand member of hand switch H, to battery and thence to ground. At the same time relay 20 will actuate a pen register of any well-known design to make a record of the condition in which the connector switch under test is found. When, an instant later, sequence switch 18 arrives in the thirteenth position, stepping magnet 16 is energized, as heretofore described, and advances the brushes b' , b^2 and b^3 to a new position.

What is claimed is:

1. In an electrical testing system, an arrangement for detecting unstandard conditions in an automatic selective switch, comprising a testing means responsive to an electrical condition on the release wire of such automatic selective switch indicating an unstandard condition, a single link conductor extending between said release wire and said testing means, automatic means for associating said testing means with said conductor, and means controlled by said testing means for indicating such unstandard condition.

2. An arrangement for detecting and recording an unstandard condition in an automatic selective switch comprising a single relay responsive to a potential indicating an unstandard condition, a signaling apparatus controlled by said relay for apprising the responsible person of such unstandard condition, recording means responsive to a potential indicating an unstandard condition, and means for preventing the operation of the recording means in case the unstandard condition is eliminated in response to the operation of such signaling apparatus.

3. An electrical testing system for detecting unstandard conditions created in an automatic selective switch through the failure of a called party to replace his receiver on its hook after the calling party has abandoned the call, comprising testing means responsive to an electrical condition at one point in the circuit of such a selective switch indicating an unstandard condition, recording means responsive to said electrical condition, and means responsive to said testing

means for preventing the operation of said recording means.

4. An electrical testing system for detecting and recording unstandard conditions in an automatic selective switch created through the failure of a called party to properly manipulate the apparatus connected with said switch, comprising testing means responsive to a changed electrical condition at one point in the circuit of such a selective switch indicating an unstandard condition, recording means also responsive to said changed electrical condition, signaling means controlled by said testing means for apprising the responsible party of such unstandard condition, and means controlled by said testing means for preventing the operation of said recording means responsive to the proper manipulation of said apparatus connected with said switch in response to said signaling means.
5. An arrangement for detecting an unstandard condition in an automatic selective switch, which is used in establishing telephonic connection and which unstandard condition is created by the improper manipulation of subscriber's apparatus, comprising contacts connected to the talking circuits of said switch and a contact connected to the release circuit of said switch, testing means responsive to a changed electrical condition in such release circuit indicating an unstandard condition of said switch, automatic means for associating said

testing means with said contacts, and means controlled by such testing means to indicate the existence of an unstandard condition.

6. An arrangement for determining unstandard conditions in an automatic selective switch used for establishing telephonic connection, comprising a single contact connected to the release circuit of said switch, testing means responsive to a potential on such release circuit indicating an unstandard condition, and means for automatically and successively associating such testing means with such contacts and with said testing conductor.

7. An arrangement for detecting and recording an unstandard condition in an automatic switch used for telephonic connection, comprising a single contact connected to the release circuit of said switch, contacts connected to the talking circuits of said switch, testing means responsive to a potential on said release circuit indicating an unstandard condition, a signaling means controlled by said testing means for apprising the responsible party of said unstandard condition, means for recording said unstandard condition, and means under control of said responsible party for rendering inoperative said recording means.

In witness whereof, we hereunto subscribe our names this 19th day of December A. D., 1916.

HENRY P. CLAUSEN.
